UNITED STATES PATENT OFFICE.

WILLIAM R. DUTEMPLE, OF AUBURN, RHODE ISLAND.

CIGAR-VENDING MACHINE.

SPECIFICATION forming part of Letters Patent No. 699,670, dated May 13, 1902.

Application filed January 8, 1902. Serial No. 38,880. (No model.)

To all whom it may concern:

Be it known that I, WILLIAM R. DUTEMPLE, a citizen of the United States of America, and a resident of Auburn, in the county of Providence and State of Rhode Island, have invented certain new and useful Improvements 5 in Cigar-Vending Machines, of which the following is a specification.

My invention relates to improvements in to "coin - controlled vending - machines," so called; and it consists in the novel construction and arrangement of the devices or instrumentalities through which the apparatus is adapted to be actuated, all substantially as 15 hereinafter set forth and claimed.

I am well aware that in a general way vending-machines heretofore devised and as usually constructed embody devices or elements adapted to be rendered operative upon inserting a coin in a slot communicating with a chute, which latter directs the coin to the releasing mechanism of the apparatus.

This machine relates to a machine adapted more especially for dispensing cigars or any 25 other articles having substantially the same form and size and capable of being dispensed singly from the machine after first placing a suitable coin therein, the coin itself forming an intervening element for coacting with the 30 releasing mechanism, thereby insuring that upon manipulating the discharge or ejector device one cigar will be forced outwardly from the machine to the purchaser.

The object of my invention is to provide an 35 improved mechanism for the agitation and delivery of cigars singly from the magazine.

The machine is provided with a glass-paned case or housing having a locked or sealed cover. The case contains a suitable receptacle 40 adapted to receive and hold the box containing the cigars, (the cover of the box being first removed,) the said box and receptacle forming a comparatively large magazine in direct communication with each other and 45 from which the cigars are dispensed or vended singly, as before stated. The lower side or end of the magazine has a visible opening therethrough for the passage of the cigars therefrom, the construction being such that 50 upon agitating the mass of cigars by any suitable means the lowest cigar in the magazine will then register with the said discharge-

opening. Now upon manipulating the discharge or ejector mechanism the said cigar will be forced endwise through the opening 55 and be delivered upon a suitably-arranged exterior shelf or bracket.

In the accompanying three sheets of drawings, Figure 1 is a perspective view showing one form of my improved cigar-vending machine. Fig. 2 is a side elevation of the holder or magazine removed from the casing and having the box containing the cigars to be vended secured thereto. Fig. 3 is a corresponding end view. Fig. 4 is a vertical sectional view taken on line 3 3 of Fig. 3, showing the relation of the cigar-agitating device to the holder. Fig. 5 is a longitudinal sectional view taken substantially through the center of the machine, as on line 6 6 of Fig. 6, the several members being in the normal position. The cigars are omitted from the drawings, except the one positioned with respect to the ejector mechanism. Fig. 6 is a horizontal sectional view taken substantially 70 on line 5 5 of Fig. 5. Fig. 7 is a transverse section taken on line 7 7 of Fig. 5. Fig. 8 is a partial plan view showing means for adjustably securing the cigar-box to the holder.

A, again referring to the drawings, designates my improved cigar-vending machine complete. The frame or casing *a* thereof may be made of suitable material, as metal or wood. The form and size may be varied from the drawings and suitably ornamented, as desired. 85 The said top portion *a'* of the casing is further provided with an extension *a'*, having transparent panels *a*³ in its top and side walls. The lower part of the casing has a vertical slot *a*⁴ formed in its front wall, through which 90 an end *f* of the cigar-agitating lever extends, as will be more fully hereinafter described. The left or delivery side of the casing is provided with a glass-covered extension *a*⁵, into which the vended cigar is discharged and 95 from which, by suitable means, it is released and falls by gravity outwardly through the opening *a*⁶ onto the ledge or bracket *a*⁷. A frame or holder *B* is removably secured within the casing, the same having an opening on 100 top adapted to receive and retain therein the box *C*, containing the cigars to be vended, as clearly shown in Fig. 2. The upper side of said box (the cover of which is first removed)

is inserted in said opening, the interior of the box then registering with the walls of the magazine m beneath. The two lower walls or sides of the magazine are united and form a 5 V-shaped depression, the apex or angle m^4 forming a seat or support for a single cigar. The box itself also constitutes a portion of the magazine, as clearly shown. In order to adapt the frame B to retain boxes varying in 10 size, both in length and width, the former is provided on top with a movable bar b , having a slot b' at each end, through which securing-screws b^2 pass. Oppositely-located swinging clips or dogs b^3 are employed to secure the box in position, as shown. The means for adjusting the magazine to receive boxes varying in width, which corresponds with the length of the cigar, consists in making the rear wall or side m' laterally movable, the adjustment being effected by means of suitably-arranged screws s . The member m' is cut away or has a transverse opening s' therethrough registering with the center of the lowest cigar in the magazine, or, in other words, 25 when the cigar is in the normal position, preparatory to being discharged from the magazine. It is through this opening that the cigar ejector or pusher, soon to be described, works. The opposite or front side wall m^2 of 30 that portion of the magazine formed in the holder B is made of transparent material, as glass, and is provided with a hole s^2 , in alignment with the said rear opening s' . The bottom wall of the magazine has two parallel longitudinally-extending slots formed 35 therein, adapted to receive the cigar-agitating device D. This latter consists of the two laterally-separated parallel blades d , forming a lever pivoted at d' and provided with an extension or handle portion f , passing through said slot a^4 of the casing a . The upper edge or working side of the lever is substantially L-shaped, its horizontal portion passing through 40 one side of the magazine and being provided with one or more suitably-arranged shallow 45 depressions or corrugations d^2 d^3 , adapted upon swinging the lever to engage with and agitate the cigars in the magazine. The other or vertically-extending part or face d^4 of the 50 lever is curved and passes through the other or left wall of the magazine, as clearly shown in Fig. 4. It will be seen that upon elevating the lever to its limit the corrugated edge thereof operates both to lift and agitate the 55 cigars, as stated, and at the same time to deflect them toward the opposite portion d^4 of the lever, said portion then being retracted past the adjacent side of the magazine. Now upon depressing the lever the part d^4 thereof 60 is projected through the adjacent side of the magazine a short distance, the result being to still further agitate the cigars, while it also at the same time gently presses them downwardly and positively insures the seating of 65 a cigar in the larger or central depression d^3 , formed at the intersection of the two portions of the working face of the lever, so that when

the latter again is in its normal or bottom position it will have carried the cigar downwardly with it into the stationary seat or 70 angle m^4 , formed in the magazine, the cigar then being in alignment with the said openings s' s^2 . I would state that after a cigar enters the depression d^3 it cannot be dislodged or unseated by a further manipulation of the 75 lever, since the relation of the side d^4 to the other part of the lever and to the magazine is such that its (the side d^4) normal pressure downwardly upon the column of cigars adjacent to it exceeds the pressure from the opposite side, the cigars at the same time rolling against one another, and thereby adapting themselves to the different forces. 80

The discharge or cigar-ejecting mechanism E consists, essentially, of a suitably-mounted 85 horizontally-extending bar e , a plunger or pusher member e' , located above, parallel with and connected to the rear portion of said bar and traveling in unison therewith, whereby the latter may be manipulated to force 90 the positioned cigar from the machine. The end of the lever e may coöperate with any suitable coin-controlled mechanism that may be located in the compartment a' . The ejector is adapted to be manipulated by means of 95 a rod r , secured to bar e and extending outwardly through the casing. The outer or free end of the rod has a knob or handle r' , as clearly shown. The pusher member e' is suitably guided and arranged in alignment with 100 and is adapted to pass through the said openings s' s^2 of the magazine, thereby ejecting the cigar from the latter, as just stated, into the inclosed glass-covered chamber e^2 of the said extension a^5 of the casing. Within this 105 chamber are arranged two short spring-pressed movable fingers e^4 , the same passing through slotted openings formed in the inclined wall e^5 . (See Fig. 7.) The said fingers when in the normal position are adapted to 110 receive and support the cigar as it is forced from the magazine, the arrangement of the several members being such that upon manipulating the ejector device to dispense a cigar a dog r^2 of the bar e , Fig. 6, will engage 115 the fingers e^4 and press them rearwardly (see dotted-line position, Fig. 7) just after the cigar has been received thereon, thereby permitting the cigar to fall by gravity and roll down the inclined wall and outwardly through 120 the throat or passage a^6 onto the shelf or support a^7 .

The manner of charging and operating my improved cigar-vending machine A is substantially as follows: The cover of the box C, 125 containing the cigars, is first removed or swung rearwardly, followed by inverting the holder B, then placing it over the said box and securing it thereto by means of the dogs b^3 . I prefer to arrange the members B and C so 130 that the "head" end of the cigars will lie contiguous to the front or delivery side m^2 of the magazine. The thus-charged holder is next reversed or returned to the normal position,

as shown in Fig. 2, and then inserted in the previously-opened casing a , followed by closing and locking the lid a' , the ejector mechanism being in the normal position shown in 5 Figs. 5, 6, and 9. It will be apparent that when the holder, &c., are returned to the operative position in the casing some of the cigars will fall into the lower portion m of the magazine. In order to insure that a cigar 10 shall be discharged by the ejector mechanism, the purchaser first vibrates the agitator D until a cigar is visibly positioned in the angle m^4 , thereby at the same time registering with the holes $s^1 s^2$, formed in the 15 two end walls of the magazine. The operator next seizes the handle member r' of the ejector and draws the latter outwardly to its limit, and thereby causes the pusher member e' to engage the adjacent or "tuck" end of 20 the cigar and force it endwise through the front opening s^3 into the chamber e^3 and onto the spring-pressed supporting-fingers e^4 , the final movement of the ejector mechanism being to press the fingers rearwardly by means 25 of the lug r^2 , thereby releasing the cigar. The latter then rolls outwardly from the chamber e^3 onto the bracket or support a^3 , thus completing the operation. I would add, however, that while the foregoing action takes place 30 the agitating device D is automatically locked in position by means of the passage of a lug r^3 of the bar e , Fig. 6, into a correspondingly-arranged notch r^4 , formed in the adjacent edge of the blades d , the latter being further 35 cut away at r^6 for the passage of the bar itself. (See Fig. 4.) Upon pressing the knob or handle r' rearwardly to its limit the several devices will again assume their normal position and relation. While the pusher e' is being 40 retracted in unison with the bar e a cigar will usually drop into and fill the space thus vacated by the pusher. In such case it is obvious that the agitating device need not be manipulated.

45 My improved cigar-vending machine is comparatively inexpensive. It is easily and quickly operated, as well as being positive in its action when manipulated as described. It is simple in construction and not liable to get 50 out of order. The cigars are in no wise in-

jured or affected by the action of the mechanism employed, and the final cigar in the box is as readily and positively dispensed from the machine as when a number are present in the magazine.

55

I claim as my invention and desire to secure by United States Letters Patent—

1. In a cigar-vending machine, the combination of a magazine having a receptacle at its lowermost portion arranged to receive a single cigar; an agitating device arranged to direct a cigar into said receptacle; an ejector arranged to enter the receptacle and move a cigar endwise therefrom; and means for preventing movement of the agitating device while the ejector is located in the said receptacle.

2. In a cigar-vending machine, the combination of a magazine having a substantially V-shaped bottom that is provided with one or more slots extending transversely to the line of convergence of the walls forming the V-shaped bottom; an agitating-lever operating in each of said slots, each lever having a depression in its cigar-engaging portion that is in alinement with the said line of convergence when the lever is in its normal position; and means for ejecting a cigar from the angular portion of the magazine.

3. In a cigar-vending machine, the combination of a magazine having a substantially V-shaped bottom that is provided with one or more slots extending transversely to the line of convergence of the walls forming the V-shaped bottom; an agitating-lever d , operating in each slot; said lever having a depression d^3 , in its upper edge that is in alinement with the said line of convergence when the lever is in its normal position; the lever also having the corrugations d^2 , adjacent the depression d^3 , and the extended portion d^4 ; and means for moving a cigar from the angular portion of the magazine.

Signed at Providence, Rhode Island, this 30th day of December, 1901.

WILLIAM R. DUTEMPLE.
